CLAIM

The ornamental design for an element for power transmission coupling as shown and described.

DESCRIPTION

FIG. 1 is a front perspective view of an element for power transmission coupling in accordance with aspects of the present subject matter.

FIG. 2 is a front view of the element for power transmission coupling illustrated in FIG. 1.

FIG. 3 is a rear view of the element for power transmission coupling illustrated in FIG. 1.

FIG. 4 is a first or left side view of the element for power transmission coupling illustrated in FIG. 1.

FIG. 5 is a cross-sectional view of the element for power transmission coupling taken about line 5-5 in FIG. 2; and, FIG. 6 is a cross-sectional view of the element for power transmission coupling taken about line 6-6 in FIG. 2.

The second or right side, top, and bottom views of the element for power transmission coupling are mirror images of the first or left side view.

Contour lines and/or surface shading, to the extent applicable, are illustrated simply for purposes of highlighting the solid-rendering, and, thus, form no part of the claimed design.

1 Claim, 6 Drawing Sheets
